(57) **CLAIM**

The ornamental design for an electrical housing as shown and described.

DESCRIPTION

FIG. 1 is a front-top-right perspective view of an electrical housing showing our new design;

FIG. 2 is a rear-top-right perspective view of the electrical housing shown in FIG. 1.

FIG. 3 is a front view of the electrical housing shown in FIG. 1.

FIG. 4 is a top view of the electrical housing shown in FIG. 1.

FIG. 5 is a rear view of the electrical housing shown in FIG. 1.

FIG. 6 is a bottom view of the electrical housing shown in FIG. 1.

FIG. 7 is a right side view of the electrical housing shown in FIG. 1.

FIG. 8 is a left side view of the electrical housing shown in FIG. 1; and,

FIG. 9 is another front-top-right perspective view of the electrical housing shown in FIG. 1 to show an environment. The broken lines in the drawings show portions of the electrical housing that form no part of the claimed design.

1 Claim, 9 Drawing Sheets
